UNITED STATES PATENT OFFICE.

ERICH SANDNER, OF LANSING, MICHIGAN, ASSIGNOR TO AMERICAN SUCTION GAS PRODUCER COMPANY, OF LANSING, MICHIGAN, A CORPORATION OF MICHIGAN.

GAS-PRODUCER.

No. 824,384.

Specification of Letters Patent.

Patented June 26, 1906.

Application filed July 31, 1905. Serial No. 272,079.

To all whom it may concern:

Be it known that I, ERICH SANDNER, a subject of the German Emperor, residing at Lansing, in the county of Ingham and State of Michigan, have invented certain new and useful Improvements in Gas-Producers, of which the following is a specification, reference being had therein to the accompanying drawings.

10 The invention relates to gas-producers, more particularly of that type known as "suction" gas-producers; and the invention consists in certain novel features of construction, as hereinafter set forth.

15 In the drawings, Figure 1 is a vertical central section through the producer. Fig. 2 is a similar view with the section taken in a plane at right angles to that of Fig. 1.

With gas-producers of the type to which 20 my improvement belongs the gas is formed by drawing a mixture of air and vapor through an incandescent mass of fuel, the suction being preferably produced by the piston of the engine in which the gas is expl-

25 osively used. The quantity of air drawn through the fuel is varied according to the suction of the engine, and the quantity of vapor is also varied by reason of the fact that the heated gases from the producer are passed

30 through the vaporizer, and therefore any increase in the volume of the gas will produce a correspondingly greater vaporization. With the present invention the vaporizer instead of being placed outside of the producer as in

35 constructions heretofore used is arranged in the center of the mass of fuel and is shaped to form a conduit through which the heated gases are drawn out from the producer. Thus the whole apparatus used for the production

40 of the gas is inclosed within the one casing, and the vaporizer being in the midst of the fuel will respond more instantaneously to any change in heat developed therein.

As shown, A is the casing, preferably of cylindrical form and provided with a suitable lining B, of fire-brick or other refractory material. As illustrated, the central portion of the mass of fuel within the casing rests upon a hearth C, and the surrounding portions are 45 supported upon a stepped grate D, arranged to form lateral air-passages through which the air and vapor are drawn into the fuel.

Extending centrally across the casing and

the fuel-chamber therein is the vaporizer E. This is preferably in the form shown having 55 an inverted-V-shaped cross-section, so as to form the opposite inclined walls a b, which permit the free passage of the fuel. The vaporizer is also provided with a central cylindrical wall c, which forms a conduit ex- 60 tending longitudinally of the vaporizer, and at one end this is connected by the coupling d with the gas-education pipe. There is also formed centrally of the vaporizer a downwardly-extending opening from the casing c, 65 through which the gases formed in the body of the fuel may enter the conduit. Between the cylindrical wall c and the outer inclined walls a b is a chamber containing the water to be vaporized, and above the water-level is 70 a sufficient space for the reception of the vapor. F is a detachable cap covering an opening in the top of the vaporizer, this cap being of upwardly-tapering form, so as to deflect the fuel upon opposite sides. 75

At the top of the casing A is a suitable fitting G, which is connected with the fuel-charging apparatus. (Not shown.) H is the conduit leading from the vaporizer to the nozzle l, and J is the air-inlet. With the apparatus constructed as described in operation the fuel from the charging apparatus is permitted to fall into the fuel-chamber within the casing A and will be directed upon opposite sides of the vaporizer, filling the chamber 85 below the same and also packing around the vaporizer and above the same. When the apparatus is in full operation, the fuel within the chamber will be in a state of incandescence, and the incoming air which passes 90 through the lateral passage-ways between the steps of the grate will be converted into a carbon-monoxid gas. With the air is mixed the vapor from the generator E, which is decomposed to form hydrogen. 95

Inasmuch as the heat developed within the mass of fuel is proportional to the combustion, it is evident that whenever there is increased combustion, due to the drawing in of a greater quantity of air, this will communicate a greater heat to the vaporizer, which will increase the amount of vapor commingled with the air. On the other hand, if the amount of air passing through the fuel has diminished the falling off in heat will decrease the vaporization and proportionately 100 105

diminish the quantity of vapor commingled with the air. Another feature of the construction is the means by which the fuel within the combustion-chamber is compelled to assume an inverted conical form immediately beneath the vaporizer. This is by reason of the fact that the fuel is fed in above the vaporizer and is deflected by the latter to opposite sides of the casing. Thus immediately below the vaporizer and the aperture connecting to the gas-outlet conduit there will be formed a hollow space. The effect of this is to form the path of least resistance for the air entering through the grate directly to the center of the mass of fuel instead of at the sides. This will result in to a large extent limiting the combustion to the center of the mass and will prevent the formation of clinkers at the sides, thereby avoiding clogging of the apparatus. Furthermore, it will be noted that with the stepped grate for supporting the fuel the air entering beneath each of the successive steps will find the path of least resistance directed toward the center, and as the fuel is consumed it will feed in from the sides toward the center, always maintaining the hollow beneath the gas-outlet and the inverted conical form to the mass of fuel.

What I claim as my invention is—

30 1. A gas-producer comprising a casing constituting a fuel-chamber through which a current of air is drawn and a hollow member extending across the fuel-chamber within said

casing constituting an eduction-conduit for the generated gas, the walls of said conduit 35 being hollow and forming a water-chamber in which vapor is generated and commingled with the air drawn through the casing.

2. A gas-producer comprising a casing forming a fuel-chamber, a hollow member 40 passing transversely across said casing and the fuel-chamber therein, the outer walls of said member being of inverted-V-shaped cross-section and the inner wall of cylindrical cross-section, the space between said walls 45 forming a water-chamber and said inner wall constituting an eduction-conduit through which the generated gases are drawn, whereby the vaporization will vary with the variation of the gas generated. 50

3. In a gas-producer, the combination with a casing forming a fuel-chamber, of the generator E therein having the oppositely-inclined and upwardly-tapering walls a, b, the inner cylindrical wall c forming a gas-education conduit and opening centrally downward into the mass of fuel and the detachable cap F at the top of said vaporizer, substantially as and for the purpose described. 55

In testimony whereof I affix my signature 60 in presence of two witnesses.

ERICH SANDNER.
